UNITED STATES PATENT OFFICE

ERNEST TALBOT, OF LOWESTOFT, ENGLAND

PISTON FOR FLUID-PRESSURE ENGINES

Application filed June 12, 1928, Serial No. 284,826, and in Great Britain November 10, 1927.

- This invention relates to pistons for fluid pressure engines, of the kind in which the head and the skirt are separately constructed and subsequently united by fasteners, the skirt being of thin cast metal, or wrought metal machined from the solid bar, or formed of drawn tube, or of sheet metal which is either pressed to shape or bent to a cylindrical or slightly oval form.
- 10 The principal object of the invention is to provide a simple and light construction which is easy to manufacture and assemble and enable a scraper ring to be fitted to a thin-walled skirt.
- 15 In the accompanying drawings, which illustrate various methods of carrying out the invention, Figure 1 is a half-section of one type of cast metal head to which is fitted a skirt machined from the solid,
- 20 Figure 2 is also a half-section showing another type of cast metal head and a skirt formed from thin sheet metal or a tube with an attachment flange formed by presswork or equivalent means,
- 25 Figure 3 shows a slight modification of the flange shown in Figure 2,
- 30 Figures 4-8 each show half-sections of alternative constructions,
- 35 Figure 9 is a full half section of another construction shown in lower end view by Figure 10,
- 40 Figures 11-13 are fragmentary sections showing details of the attachment means,
- 45 Figure 14 is a half-section showing the provision of a groove for a scraper ring independently of the attachment flange, and
- 50 Figure 15 shows the employment of a fixing device for the gudgeon pin as applied to a construction corresponding to Figure 14.
- In Figure 1 the skirt 2 is formed in one piece by machining from the solid bar, the exterior being plain, whilst the interior has formed on it an inner radial flange 3 of a thickness at the root sufficient to provide for a ring groove 4 being machined in it, leaving an adequate thickness of metal for the walls of the groove. The depth of the flange beyond the groove is sufficient to accommodate fasteners 5 extending through it to secure
- the skirt to a jointing face 6 on the cast piston head 7.
- The latter may be of any usual construction in which the gudgeon pin bosses 8 are carried integrally or otherwise upon it. Thus, below the upper portion in which grooves 9 of the ordinary packing rings are provided, the diameter of the head is reduced as at 10 to the desired extent to provide an annular space 11 between the reduced portion and the separately formed skirt. Alternatively, as shown by Figure 2, the cast head may be constituted by a crown 12, a depending flange 13 around it containing the packing ring grooves 9, and a tubular neck 14 extending from the underside of the crown (distinct from the ring-carrying flange) and supporting the gudgeon pin bosses 8, or again, the latter may be carried merely by webs extending from the crown and its ring-carrying flange.
- The undersides of the bosses 8 are sufficiently thick for the formation with the face 6 of a concentric shoulder 15 against which the inner edge of the flange 3 can abut. Obviously, if desired, the face 6 and shoulder 15 may be on a ring which ties the two gudgeon pin bosses together, giving a more secure engagement for the flange 3.
- It will be evident that the construction just described is equally applicable to a skirt formed of cast metal instead of being machined from the solid.
- The skirt shown in Figure 2 is a wrought metal tube and the flange 16 is formed by rolling, swaging, or otherwise inwardly pressing the skirt to form a groove which either may be partially flattened as shown to leave a space as at 4 for a ring, or alternatively is completely flattened as in the detail Figure 3, or in Figures 14 and 15, when a further groove for a ring, if desired, may be located above or below the flange (see for example Figure 14). Other details of the connection of skirt and head may be as described for Figure 1.
- The skirt shown in Figure 4 is formed of two parts, either of drawn tube or by pressings from sheet metal, or by rolling sheet metal into cylindrical form, the adjacent

ends of the two parts of the skirt being flanged inwardly as at 17 and 18 to form the connecting means and the sides of the ring groove. Between them is inserted a distance ring 19, and this at its outer periphery forms the bottom of the groove, the fasteners extending through it and through the flanges 17, 18. These parts are accurately registered as already described by means of the shoulder 15.

The distance ring may be provided in one face with one or more annular grooves 20 from which extend outwardly any desired number of radial grooves 21. Thus oil collected by a ring placed in the groove 4 is conveyed to the annular groove 20, and thence it can be delivered to any desired spot within the skirt by a passage such as 22 extending in the direction of motion of the piston so that the oil is readily dispersed upwardly or downwardly.

By a modification shown in Figure 5, the distance ring between the two flanges can be integrally formed with one or both of the flanges as at 23, that is, either partly on each or wholly on the one flange. In this case the flanges are folded back upon themselves to form the ring.

To suit a thin walled one-piece skirt of wrought metal having a ring groove formed by rolling, the position of the groove is such that it will engage in an angle seating as formed by the faces 6 and concentric shoulder 15. A distance ring 24 is shown in Figure 6 at the bottom of the groove and may be in two or more segments to enable it to be entered. If the groove is sufficiently deep the several parts may be retained in position by causing the fasteners 5 to extend through them.

To avoid the necessity for machining the sides of the groove formed for the ring, a die in the form of a split ring may be provided so as to enter in the roughly formed groove from the outside, and the outer sides of the groove can then be subjected to pressure from opposite sides to close them against the sides of the die and form an accurate groove.

If it is not desired, with a groove thus formed, to provide the distance ring 24, one side of the groove (see Figures 2 and 7) may have formed around it a step 25 adapted to form a radial stop for a scraper ring inserted in the groove. The effect of this step is to give to the groove a contour such as would be required for an L-shaped ring, if such type is preferred. In Figure 7 the space beyond the step is not shown as sufficiently wide for such a ring but serves merely as a collecting groove for lubricant which is then discharged by the passage 26. For such a form of attachment flange 27 it is preferred that the fasteners 5 should not extend through the bottom of the groove but through a

clamping plate or ring 28 which at its edge lies over the outside surface of the flange 27 to grip it to the face 6. Such a clamping plate could be used for the fixing means in the construction Figure 2 where the sides of the groove are flattened into contact, or for those shown in Figures 6 and 8. In Figures 9 and 10 are shown how the heads of the fasteners 5 may enter cut-away portions 50 in the step 25. Whilst the seating 6 may extend from one gudgeon pin boss to the other, it is preferred to avoid adverse expansion effects (through dissimilar metals of the head and skirt) by leaving a gap 60 between the tensions of the seating surface 6.

This gap may be narrow as shown or considerably wider, and the shoulder 15 now engages the side of the skirt which is formed or machined to suit.

In Figure 11 a two-part skirt is shown with a step 25 in each flange to form a ring groove, and the seating 6 has a second concentric shoulder 150.

The step 25 shown both in Figure 2 and Figure 7 may be on the opposite side of the attachment flange as in Figure 12. Figure 13, however, is as in Figures 2 and 7 but shows a clamping ring 280 of thicker metal than that at 28, and fits at its edge on the inward face of the step 25. In Figure 12, however, the clamping ring is omitted and the fixing is as in Figure 2, and a shoulder 150 is formed in addition to that at 15.

If it is preferred not to step one side of the groove nor to put a distance ring between its sides, then slits 29 (Figure 8) may be made in its base to form tongues 30 which can be bent outwardly. The edges 31 of these tongues thus form stops limiting the radial movement of a scraper ring mounted in the groove 4, whilst the apertures due to the slits 29 serve for the escape of oil from the groove.

In any of the above constructions, holes 32 for giving access to the gudgeon pin bearings may be provided. Also the upper edge 33 of the skirt and the ring-carrying portion of the head may abut as in Figure 2, the edge of the skirt preferably being turned inwards for the purpose, as by spinning or beading, or they may be spaced as shown in Figure 1, or so arranged as to provide for a packing or scraper ring to be located between them (see Figure 9).

Instead of forming the tongues 30 in the base of the ring groove, they may be formed in one or both of the side walls (see Figure 11). This has the advantage that at the same time apertures 34 are provided in the side walls of the groove for escape of the lubricant. Tongues on each side of the groove can be in staggered relationship with one another, and preferably with the apertures directly opposite one another. Thus the tongue on one side of the groove would be op-

posite to the free edge of the aperture on the other side thereof.

The advantage of providing a radial attachment flange completely flattened as in Figure 3 and without a groove for a packing ring is that the latter may now be placed at a position 35 which is more convenient for certain types of engines, i. e., nearer to the free edge of the skirt (see Figures 14 and 15). Also it allows the gudgeon pin to be retained by a particular device inserted between the end of the pin and the skirt. Thus, if a scraper ring is located at a position between the radial flange and the free edge of the skirt, the gudgeon pin retainer, illustrated at 36, Figure 15, may be adopted, as the resilient loop 37 at its lower end will then clear the inwardly projecting wall of the groove 35 to engage the ledge or inturned bead 42 at the end of the skirt. Alternatively, another construction (not illustrated) may be adopted in which the retaining device is secured by the fasteners 5 connecting the head and skirt. In applying either of these two constructions to the present invention, a space 38 is provided between the end of the gudgeon pin boss 8 and the inner side of the skirt, and, as the retaining device extends into this space across the end of the gudgeon pin, it is necessary to pierce as at 39 the radial flange 16 by which the connection of the skirt and head is made, so as to allow for the passage through it of the retaining device.

In connecting the head and skirt, particularly when the latter is formed of very thin metal, it is preferable to employ four attachment bolts or screws and to make the contacting area on the face 6 of approximately equal area on each side of the bolt. This reduces the risk of distortion when the bolts are tightened. It will be seen that oil grooves may be provided as required at the positions 40 near the upper edge of the skirt and 41 in the scraper ring groove for the escape of lubricant collected at either of these positions.

From the foregoing it will be seen that the invention provides a simple, light and inexpensively constructed piston having ample provision for a scraper ring at any position above the lower edge of the piston, without sacrificing the valuable bearing surface existing between the gudgeon pin and the usual packing rings where ordinarily space is very limited.

What I claim as my invention and desire to secure by Letters Patent of the United States is:—

1. In a piston, the combination of a cast metal head formed with gudgeon pin bosses, a concentric shoulder on said head, a thin metal skirt, an inward flange formed around the whole periphery of said skirt, said flange having a concentric shoulder at its inner

edge which registers with that on the head, and means for attaching said flange to said head.

2. In a piston, the combination of a cast metal head formed with gudgeon pin bosses, a concentric shoulder on said head, a thin metal skirt, an inward flange thereon whereby it is attached to said head, said flange forming a groove the sides of which thereafter are closely pressed together, and means for attaching said flange to said head. 75

3. In a piston, the combination of a cast metal head formed with gudgeon pin bosses, a concentric shoulder on said head, a thin metal skirt, an inward integral flange thereon whereby it is attached to said head, said flange forming a groove adapted to contain a spring ring and compressing together the sides of the groove on the inner edge of the ring and means for attaching said flange to said head. 80

4. In a piston, the combination of a cast metal head formed with gudgeon pin bosses, a concentric shoulder on said head, a thin metal skirt provided with an inturned top and bottom, an inward annular ring carrying flange formed around the whole periphery of said skirt, said flange having a concentric shoulder at its inner edge which registers with that on the head, and means for attaching 90 said flange to said head. 95

In testimony whereof I have signed my name to this specification.

ERNEST TALBOT.
